UNITED STATES PATENT OFFICE.

MASON R. WELTY, OF HUNKERS, PENNSYLVANIA.

MACHINE FOR GRINDING AND POLISHING PLATE-GLASS.

SPECIFICATION forming part of Letters Patent No. 684,330, dated October 8, 1901.

Application filed January 3, 1901. Serial No. 42,000. (No model.)

To all whom it may concern:

Be it known that I, MASON R. WELTY, a citizen of the United States, residing at Hunkers, in the county of Westmoreland and State 5 of Pennsylvania, have invented certain new and useful Improvements in Machines for Grinding and Polishing Plate-Glass; and I do hereby declare the following to be a full, clear, and exact description of the invention, 10 such as will enable others skilled in the art to which it appertains to make and use the same.

The object of this invention is to minimize the danger of breaking plate-glass during the process of grinding, smoothing, and polishing, 15 by materially reducing the handling and to enable the finishing to be effected in a less time and at a diminished cost than is possible by the method generally in use.

The organized machine embodies a revolvable plate-holder and a stationary grinder or polisher, the latter being interchangeable, so that the grinder may be replaced by the smoother and polisher.

The invention consists of the novel features, details of construction, and combinations of parts, which hereinafter will be more fully described and claimed, and shown in the drawings hereto attached, in which—

Figure 1 is a front view of a machine embodying the invention. Fig. 2 is a side elevation of the truck provided with the grinding elements. Fig. 3 is a view similar to Fig. 2 of the truck provided with buffers or polishers. Fig. 4 is a transverse section of the truck supplied with the grinding and smoothing elements and showing the means for supplying abrading material thereto and the revolvable holders for the plate-glass to be operated upon. Fig. 5 is a perspective 40 view of a revolvable holder. Fig. 6 is a detail view of the instrumentalities whereby the revolvable holder is controlled and the plate-glass automatically fed to the grinder or polisher. Fig. 7 is a detail view of a portion of the polisher. Fig. 8 is a detail view of the means for holding the truck when positioned 45 between the revolvable holders.

Corresponding and like parts are referred to in the following description and indicated 50 in all the views of the drawings by the same reference characters.

The shafts 1 and 2, mounted in bearings

provided at the lower end of swinging brackets or hangers 3, are provided at their inner ends with plates or heads 4, constituting revolvable holders to which the plates of glass to be ground and polished are attached. These shafts are rotated either in the same or opposite directions and at the same time receive a to-and-fro movement, resulting from an oscillatory movement imparted to the hangers or brackets 3. Any suitable mechanism may be employed for rotating the shafts and oscillating the hangers, and the latter may be vibrated in unison in the same or opposite 60 directions. The swinging movement of the shafts prevents the formation of rings or lines upon the surfaces of the glass plates. The heads or revolvable holders 4 may be of any dimension according to the size and capacity of the machine, and in order to secure the glass plates thereto the holders are provided with clamp-bars 5, attached thereto in any desired and substantial manner. The shafts 1 and 2 are mounted so as to have a 70 limited longitudinal or endwise play, which is essential in order to make provision for an automatic feed of the glass plates as the grinding or smoothing progresses. This construction also admits of the revolvable holders being moved outward to allow the truck carrying the grinders or buffers to pass readily between the plates either in or out.

A bracket 6 is provided at the outer side of each hanger 3, and a set-screw 7 passes through the lower end thereof and makes screw-thread connection with the outer end of the shaft, a spring 8 being mounted upon the set-screw and interposed between the bracket and outer extremity of the said shaft and normally tending to move the latter inward to force the plates of glass against the polishers or buffers. Upon turning the screw 7 so as to cause it to enter the threaded opening in the outer end of the shaft the latter is moved outward and the spring 8 compressed, and after the truck has been moved into position between the holders the set-screws are turned in the opposite direction to permit an expansion of the springs 8, whereby the shafts are moved inward to carry the glass plates against the grinders, and as said plates are ground they are automatically fed forward by the action of the springs, as will be readily comprehended.

A truck 9, of suitable construction, is adapted to travel upon rails 10, constituting a track and extending parallel with the revoluble holders 4. The longitudinal sills of the truck 5 are extended at their ends, as shown at 11, and securing means coöperate therewith to fix the position of the truck when located between the revoluble holders, so as to admit of the grinders or buffers acting upon the glass 10 plates attached thereto. Pendent from each extension 11 of the sills is a rod or bar 12, and these parts serve to properly position the truck and to hold it in place. Guides 13 are applied to the sleepers 14, upon which the rails 10 are 15 mounted, and consist of a base-plate and vertical flanges 15, extending about in parallel relation and flaring at their ends to admit of the free entrance therebetween of the lower ends of the rods or bars 12. When running 20 the truck between the revoluble holders 4, the lower ends of the rods or bars 12 pass between the flanges 15 of the respective guides and fix the position of the truck and prevent lateral movement thereof, vertical and longitudinal movement being prevented by clamps, 25 consisting of arms 16, pivotally connected at their lower ends to the sleepers 14 and having their upper ends bent and threaded to receive clamp-screws 17, which are adapted to turn against the top side of the extensions 11, so as to clamp said extensions between the 30 guides 13 and the clamp-screws 17. By having the arms 16 pivotally connected to the sleepers 14 or other convenient portion of the machine they can be turned down out of the 35 way, so as to admit of the truck to be run into or away from the machine.

Mounted upon the truck is the grinding or polishing mechanism, as desired, and in this 40 connection it is to be understood that different trucks are provided for the same machine, each being supplied with finishing mechanism either for grinding, smoothing, or polishing, as required in the operation of treating 45 the glass plate for the market. These trucks are interchangeable—that is to say, the truck bearing the grinding mechanism is replaceable by the truck bearing the smoothing devices and the latter in turn adapted to be substituted by the truck bearing the buffers or 50 polishing elements. The superstructure of the truck bearing the grinding mechanism comprises upright boxes 18, closed at their bottom and sides and open at their top and 55 having their outermost walls perpendicular and parallel throughout their extent and their inner walls outwardly convergent, whereby the spaces formed between the inner and outer walls of each box flares or gradually 60 widens toward its upper end, which is of advantage, as will appear hereinafter. The end and inner walls of each box are closed, whereas the outer wall is composed of a series of 65 slats or bars 19, spaced apart and provided with the grinders 20, consisting of bars 20^X, either of metal or wood and of varying length and applied to the slats 19 so as to break joint,

as shown most clearly in Fig. 2. The edges of the bars 20^X are beveled and their outer faces are formed with grooves 21 to provide 70 passages to admit of the abrading material passing from one grinder to the other in the operation of the machine. The strips or slats 19 are spaced apart, and the grinders 20 are likewise spaced so as to admit of the abrading material passing from within the box or chamber to the surface of the glass plate to be ground. Deflecting strips, bars, or plates 22 are located at different points throughout the space of the boxes 18 and incline outward 80 and downward, as shown most clearly in Fig. 4, and serve to direct the abrading material to the grinders and the plate being ground. These deflectors 22 are located so as to supply the abrading material to every part of the surface 85 of the glass plate. The abrading material is supplied to the upper end of the box-like structure 18 and in its descent is arrested by the deflectors 22 and directed to the work in the manner stated. Suitable means may 90 be employed for supplying the abrading material to the upper ends of the boxes 18, and, as shown, hoppers 23 are located above the space formed between the revoluble holders 4. These hoppers receive a supply of sand 95 and water, and their lower ends are perforated or otherwise constructed to admit of the escape of the sand and water, so as to enter the boxes 18 when the grinding-truck is in position.

The superstructure of the polishing-truck consists of vertical walls composed of spaced slats or strips 24 and buffers or polishers attached thereto. These polishers or buffers consist of plates or disks 25, formed with 105 stems 26 and covered with chamois, felt, or other soft material 27. The stems 26 enter openings formed in the bars or strips 24, and springs 28 are provided to force the buffers or polishers outward against the surface of 110 the plate being polished or finished. The polishing material is supplied to the buffers by hand, the attendant passing between the walls and applying the material to the surface by means of a brush, which is forced 115 into the spaces formed between the buffers. The vertical walls are suitably stiffened and strengthened by braces 29.

The plates of glass after being rolled and required to be ground and polished are attached to the holders 4 by means of the clamp-bars 5, and said holders are drawn outward by manipulation of the set-screws 7 in the manner stated, after which the grinding-truck is moved into position between the 125 plates and is secured by the clamp devices in the manner stated. Motion being imparted to the shafts 1 and 2, the holders bearing the plates are rotated and simultaneously oscillated, and the set-screws 7 being slackened 130 the springs 8 reacting force the plates against the grinders, by means of which the plates of glass are ground upon one side. After the plates have been sufficiently ground and

smoothed the grinding-truck is replaced by the polishing-truck and the operation repeated until the glass plates have the ground surfaces properly polished. After this operation the plates of glass are reversed and finished upon the opposite side. It is to be understood that the plates are held perpendicular throughout the entire operation and are only required to be handled once from start to finish, this handling being necessary in order to present the reverse side for finishing. The provision of different trucks enables successive steps being effected without requiring the handling of the plates, which is highly objectionable, because of the liability to breakage during each shifting or handling of the plates.

Within the purview of the invention changes in the form, proportion, and minor details of construction may be resorted to without departing from or sacrificing any of the advantages thereof.

Having thus described the invention, what is claimed as new is—

1. In a machine for grinding and polishing plates of glass, revoluble work-holders spaced apart, and a grinder or polisher adapted to be moved into the space formed between the said work-holders, substantially as set forth.

2. In a machine for grinding and polishing plates of glass, revoluble work-holders spaced apart and provided with means for attachment thereto of the glass plates, a truck adapted to be run into the space formed between the said work-holders, and means mounted upon the said truck for finishing the work, substantially as specified.

3. In a machine for grinding and polishing plates of glass, transversely-spaced revoluble work-holders, a truck provided with grinding or polishing mechanism and adapted to be run into the space between the said work-holders, and means for securing the truck when in position, substantially as set forth.

4. In a machine for grinding and polishing plate-glass, transversely-spaced revoluble work-holders, a truck provided with grinding or polishing mechanism, means for guiding the truck when run into the space formed be-

tween the said work-holders, and clamp devices for securing the truck when positioned, substantially as set forth.

5. In a machine for grinding and polishing plate-glass, transversely-spaced revoluble work-holders, a truck provided with grinding or polishing mechanism and adapted to be run into the space formed between said work-holders, guides composed of pins or bars, and spaced flanges having their end portions flared, and clamp devices for fixing the truck when properly positioned, substantially as set forth.

6. In a machine for grinding and polishing glass plates, transversely-spaced revoluble work-holders, a truck having end extensions and provided with the grinding or polishing mechanism, rods or bars pendent from the truck, spaced flanges having their end portions flared and adapted to coöperate with the said rods or bars to properly position the truck, and clamp devices coöperating with the said guide devices to secure the truck when positioned, substantially as set forth.

7. In a machine for grinding and polishing plate-glass, a revoluble work-holder, a box-like structure having one wall composed of interspaced grinding elements, deflectors located in the box and inclined outwardly and downwardly to direct the abrading material to the work, and means for supplying abrading material to the upper portion of the box-like structure, substantially as set forth.

8. In a machine for grinding and polishing plate-glass, transversely-spaced revoluble work-holders provided with means for securing the plates of glass thereto, a truck adapted to be moved toward and from the space formed between said work-holders and provided with said grinding mechanism, guide devices for properly positioning the truck, and clamp devices for securing the truck when positioned, substantially as set forth.

In testimony whereof I affix my signature in presence of two witnesses.
